UNITED STATES PATENT OFFICE.

THORNTON A. SHINN, OF COOLBAUGH'S, PENNSYLVANIA.

DESIGN FOR A CHAIN-LINK.

SPECIFICATION forming part of Design No. 17,364, dated May 31, 1887.

Application filed April 29, 1887. Serial No. 236,592. Term of patent 11 years.

To all whom it may concern:

Be it known that I, THORNTON A. SHINN, a citizen of the United States, residing at Coolbaugh's, in the county of Monroe and State of Pennsylvania, have invented and produced a new and original Design for Chain-Links; and I do hereby declare the following to be a full, clear, and exact description of the invention, such as will enable others skilled in the art to which it appertains to make and use the same.

The design relates to a link for chains; and it consists of a link distinguished by its peculiar shape, which will be hereinafter set forth and claimed.

15 In the accompanying drawings, Figure 1 is a perspective view of the link with one edge uppermost. Fig. 2 is a perspective in a reverse position. Fig. 3 is a longitudinal edge view.

20 Like letters denote like parts.

In my newly-designed chain-link the body A is shown as having a general rectangular configuration, which surrounds an elongated or rectangular opening, B. At one end of this 25 skeleton rectangular outline one of the longer side bars is extended in a right-angled pro-

jection, C and C', in the plane of the link-body, which projection terminates in a cross-piece, D, lying in a direction perpendicular to that of the link-body. The cross-piece may be of 30 a rectangular, diamond, or other shape, and its outer face provided or not, as desired, with any ornamentation, as E.

What I claim is—

1. The design for a chain-link, as herein described and shown, consisting of the skeleton rectangular outline of the link-body, one of whose sides is extended in a right-angled projection terminating in a cross-piece, substantially as set forth. 35

2. The design for a chain-link, as herein described and shown, consisting of the skeleton rectangular outline of the link-body, one of whose sides is extended in a right-angled projection terminating in a cross-piece with ornamentation thereon, substantially as set forth. 40 45

In testimony whereof I affix my signature in presence of two witnesses.

THORNTON A. SHINN.
